United States Patent Office

Des. 228,324

Patented Sept. 11, 1973

228,324

CHAIR OR SIMILAR ARTICLE

Henning Korch, Lugano, Switzerland, assignor to Burris Industries, Incorporated, Lincolnton, N.C.

Filed Jan. 19, 1972, Ser. No. 219,196

Term of patent 7 years

Int. Cl. D6—02

U.S. Cl. D6—47

FIG-2

FIG-5

FIG. 1 is a front perspective view of a chair showing my new design;

FIG. 2 is a front elevational view thereof but on a smaller scale;

FIG. 3 is a side elevational view thereof also on a smaller scale;

FIG. 4 is a top plan view thereof also on a smaller scale; and

FIG. 5 is a rear perspective view thereof also on a smaller scale.

I claim:

The ornamental design for a chair or similar article, substantially as shown.
